UNITED STATES. PATENT OFFICE.

ARTHUR N. DEAN, OF SPOKANE, WASHINGTON, ASSIGNOR OF ONE-HALF TO DOERR-MITCHELL ELECTRIC COMPANY, OF SPOKANE, WASHINGTON.

ANTISLIPPING TREAD STRUCTURE.

1,176,436.

Specification of Letters Patent.

Patented Mar. 21, 1916.

Application filed September 28, 1915. Serial No. 53,079.

To all whom it may concern:

Be it known that I, ARTHUR N. DEAN, a citizen of the United States, residing at Spokane, in the county of Spokane and State of Washington, have invented certain new and useful Improvements in Antislipping Tread Structure, of which the following is a specification.

This invention relates to improvements in tread surfaces which are especially adapted for smooth portions of a sidewalk or the like, the object being to present anti-skid or slipping surfaces so as to avoid personal injuries which frequently occur as pedestrians traverse man-holes, steel doors and other normally smooth surfaces incorporated in a tread surface or sidewalk. In view of the fact that devices of this character are subjected to continuous and severe wear, because of their use on sidewalks in populous districts, it is essential to provide tread-heads or buttons of such a character as to retain their efficient properties to prevent slippage of the foot of the pedestrian, without presenting to the foot of the pedestrian a too great inequality of tread surface.

It is one of the objects of this invention to provide an improved tread-head which is of hollow construction and which presents its open side to the foot of the pedestrian, the hollow head having an upstanding flange of such contour as to present a slippage resisting surface or edge to the foot of the pedestrian irrespective of the direction in which the latter may be walking.

A further object of the invention is to provide the tread-heads with one or more interrupted portions, as regards the flange thereof, so as effectively to drain the hollow tread-heads from accumulation of water and snow which might otherwise cause freezing, thereby reducing the efficiency of the device in preventing slippage.

A further object of the invention is to provide a two part tread device, one part comprising a hollow button, and the other part comprising a shank which is adapted to be anchored in or driven into the sidewalk structure, and which is tapered in such a manner that when it is driven into a metal door, or the door frame thereof, it need not be riveted on the reverse side, unless such reverse side is accessible to a workman.

Other features and objects of the invention will be more fully described in connec-

tion with the accompanying drawing and will be more particularly pointed out in and by the appended claims.

In the drawings:—Figure 1 is a view in side elevation of my improved tread device shown incorporated in a portion of a steel door, forming a part of a tread surface or sidewalk. Fig. 2 is a vertical sectional view on line 2—2 of Fig. 1. Fig. 3 is a plan view thereof. Fig. 4 is a plan view of a portion of a steel door arranged flush with a sidewalk and showing the application thereto of the device of my invention both as regards the frame and the doors proper.

Like characters of reference designate similar parts throughout the different figures of the drawing.

As illustrated, 1 designates a substantially cup-faced tread button preferably provided with a flat base 2 which is adapted to be disposed upon the tread surface to which the device is to be attached. The base 2 is provided with an opening 3 which is shown counter-sunk, for projection therethrough of a stud which will be presently described. I have herein shown the tread button as being circular in contour and the same is provided with an upstanding flange 4 of substantially cylindrical form. At one or more points, I interrupt the flange 4 by forming openings 5 which preferably extend down to the base 2 so as to open the inclosed portions of the button to proper drainage for release of accumulated water or snow as the latter may melt. The upper edge 6, of the flange, as well as the corners 7, of the openings 5, present effective tread edges which function to prevent slippage of the foot of the pedestrian irrespective of the direction in which the latter is walking.

Because of the tread edge 6 being interrupted, and presenting independent sections, it will be seen that as the flange wears down its slippage resistant properties will in no way be reduced until the flange has worn down flush with the face 2. Furthermore, it will be noted that any wear that takes place, would have to reduce the flange throughout its cross section, which, together with the fact that I make the button of hardened metal, would greatly prolong the life of the button even under the hardest usage.

My improved device includes an anchoring stud which is projected through the opening 3, and which is preferably pro-

vided with a flange 8, herein shown as counter-sunk, to provide a grip upon the base 2 and hold the button in position. A special feature of this invention resides in providing the stud with a tapered shank 9, preferably of softer metal than that of which the usual steel doors 11' and steel door frames 12, of sidewalks are constructed, the novel feature being to permit of the stud being driven through a previously formed opening in the door or door frame without riveting the tapered shank on the reverse side of the door or door frame. The tapered shank, together with the fact that the shank is of softer metal than the steel doors, provides for a very firm and secure anchorage of the stud with the assembling operation reduced to great simplicity. When these sidewalk door frames are initially equipped with studs, there is no way in which they can be renewed because of the fact that studs heretofore made require riveting on the reverse side, and the reverse side of a door frame is not accessible from the underside of the sidewalk. Thus with my invention, these frame studs can readily be renewed when desired without removing the frame from the sidewalk. The advantages of this feature will be appreciated in cases where door frames are so incorporated in a sidewalk structure so that they can not be removed. My improved stud is also provided with an upwardly projecting anvil head 10 which is considerably reduced in diameter with respect to the shank 9. The head 10 and flanges 8 provide for driving impact of the hammer or other implement or mechanism with which the stud is to be driven into anchored relation with a door or door frame, and I preferably make the head 10 of sufficient length so that it will project slightly above the flange 6. One reason why the head is of such length, is to facilitate the operation of driving the stud into position, and a further reason may be to give an added efficiency to the tread resistant surfaces and protect the flange section 6 against undue wear. By reference to Fig. 2, it will be seen that the sole or heel of the shoe of a pedestrian would seldom engage the flange 4 without resting against or upon the head 10.

In providing an anti-skidding tread surface, it is desirable to retain dirt, sand and other like matter which may accumulate, and therefore I reduce the drain openings 5,

with respect to the circumferential lengths of the flanges 4 so as not to release such dirt from the interior of the button, too freely, as there is no objection to its retention in the button. However, the drain openings are of such a nature, extending from the base 2, upwardly, that they would be effective in draining off water.

It is believed that the novelty and utility of my invention will be fully understood from the foregoing description, and while I have herein shown and described one specific form of my invention, I do not wish to be limited thereto except for such limitations as the claims may import.

I claim:

1. In a tread device for sidewalks and the like, a case hardened button having a base adapted to rest upon a tread surface and provided with an opening in said base, said button having an upstanding flange presenting a tread edge and said flange being interrupted to form a drain passage, and a relatively soft anchoring stud having a flange engaging said base and being provided with a tapered lower shank projecting through said opening for anchorage in the structure of the sidewalk, the upper end of said stud being shaped to form an anvil head and projecting slightly above said flange, substantially as described.

2. A tread device for sidewalks and the like, comprising in combination, a button having a base adapted to rest upon the tread surface of the sidewalk and provided with an opening therein, said button having an upstanding flange presenting a tread edge and said flange being interrupted to form a drain discharge, and an anchoring stud having a flange engaging said base and provided with a lower tapered shank projecting through said opening for anchorage in the structure of the sidewalk, the upper end of said stud being shaped to form an anvil head, substantially as described.

3. A tread device for sidewalks and the like comprising in combination, a button having a base adapted to rest upon the surface of the walk and provided with an upstanding flange presenting a tread edge, a portion of said flange being interrupted to provide a drain discharge, a means for anchoring said button upon the surface of the walk, substantially as described.

In testimony whereof I affix my signature.
ARTHUR N. DEAN.
